WILLIAM M. KELLY, OF WESTFIELD, NEW JERSEY, ASSIGNOR TO AMERICAN TYPE FOUNDERS COMPANY, OF JERSEY CITY, NEW JERSEY, A CORPORATION OF NEW JERSEY

SIDE REGISTER DEVICE

Application filed April 5, 1929. Serial No. 352,822.

This invention relates to sheet registering mechanism for paper handling machines and particularly to side gauge mechanism.

The general object of the invention is to simplify mechanism of this character and to render it more certain and accurate in the performance of its function. For the attainment of this object the invention provides a sheet registering mechanism in which the number of operating elements is reduced to a minimum while retaining and enhancing the precision of action of more complicated mechanisms.

A more particular object of the invention is to provide a side register mechanism which is adapted to be installed at either side of a feed board without alteration.

Other specific objects and advantages of the invention will become apparent from the following detail description.

Referring to the accompanying drawings:

Figure 1 is a side elevation of the sheet registering mechanism embodying the invention;

Figure 2 is a plan view;

Figure 3 is a sectional view showing the mechanism in end elevation;

Figure 4 is a section on line 4-4 of Fig. 2;

Figure 5 is a section on line 5-5 of Fig. 2;

Figure 6 is a section on line 6-6 of Fig. 4;

Figure 7 is a perspective detail; and

Figure 8 is a perspective view of the register plate.

The mechanism comprises, in general, a pull guide mounted to reciprocate transversely of the feed board adjacent the cylinder of a press, or other sheet impression means; a register plate against which the sheets are shifted by the pull guide, and cam mechanism associated with the register plate and adapted to control the opening and closing of the pull guide finger.

The pull guide is carried by a bracket 10 adjustably fixed on a bar 11 which extends transversely of the feed board and is mounted to reciprocate longitudinally in proper timed relation to the operation of the feeder and press. So far as the present invention is concerned, any suitable mechanism may be used for reciprocating the bar 11, such for exam-

ple as shown in my Patent No. 1,683,195 granted September 4, 1928.

Bracket 10 is channeled on its under side so as to fit over lateral flanges 12 of bar 11, the bracket being slideable on the bar to permit adjustment and a set screw 13 being provided to clamp the bracket in adjusted positions. Fixed to the under side of bracket 10 by countersunk screws 14 is a plate 15 adapted to coact with pull guide fingers 16 to grasp the margin of a sheet and pull it laterally on the feed board against the plate or abutment 37. There are shown two fingers 16 each formed of a plate disposed vertically with its upper and lower edges parallel and its front edge inclined to plate 15. These fingers are loosely pivoted at opposite sides of an arm 17 on the ends of a pin 18 projecting laterally from the arm. It will be observed that the pivot axis of the fingers is eccentric with respect thereto being nearer the sheet engaging ends of the fingers, so that the fingers will tend to rotate clockwise, looking at Fig. 1, when arm 17 is rotated upwardly about its pivot 19, providing with plate 15 a throat for the entry of the sheet margins. It is also to be observed that the lower, or sheet engaging, edges of the fingers will lie along the surface of plate 15 when the fingers are closed on a sheet forming parallel lines of contact with the sheet of considerable extent.

Arm 17 is pivoted on a pin 19 secured in upwardly projecting ears 20 of bracket 10, and is adapted to be automatically oscillated to open and close the fingers by mechanism hereinafter described. The arm extends from pivot 19 in an upwardly and outwardly inclined direction and then, in the form of a tubular barrel 21, in an upwardly and inwardly inclined direction, and adjacent the angle between these portions the arm is formed with integral shoulders, or abutments, 22, 22', projecting laterally from opposite sides of the arm. Screwed in the bore of barrel 21 is a pin 23 having a reduced lower end around which is the upper end of a coil spring 24, the lower end of which rests in a vertical socket 25 formed in bracket 10. This spring bears at its upper end

against the shoulder formed by the reduced portion of pin 23 and tends to hold arm 17 and fingers 16 down. The upper end portion of pin 23 has flat sides, as shown in Fig. 5, and slidably thereon is a sleeve 26 having a knurled periphery, the sleeve being non-rotatable with respect to the pin. The sleeve is pressed down on barrel 21 by a spring 27 which is compressed against the upper end 10 of the sleeve and the head of pin 23, and the sleeve is normally locked from rotation with respect to the barrel by engagement of detents 28 on the barrel with notches in the sleeve. In order to adjust the tension of spring 24, the sleeve 26 is raised against the action of spring 27 until the detents 28 are disengaged from the notches, whereupon the sleeve is turned to rotate the pin 23 and raise or lower it, as the case may be, the detents 20 being again seated in the notches after the adjustment has been made.

The register plate is mounted on a bracket 30 secured to a stationary bar 31 arranged parallel and adjacent to the bar 11, between the latter and the delivery end of the feed board. This bracket is secured to the bar by a screw bolt 32 which screws into the bar and passes through a longitudinal slot 33 in the foot of the bracket and is provided 25 with a washer 34, whereby the bracket is adapted to be clamped in adjusted positions on the bar. The bracket is formed with marginal vertical flanges 35 (Fig. 3) extending downwardly and adapted to engage the upper side edges of the bar 31, whereby lateral movements of the bracket with respect to the bar are prevented.

Bracket 30 has an upstanding portion in which is formed a horizontal threaded bore 40 for the reception of an adjusting screw 36, (Fig. 5) which has a cylindrical knurled head. This head provides a seat against which the register plate 37 is yieldingly held by a spring pressed pin 38, which is slidably mounted in an axial bore of screw 36. The register plate is formed with a circular aperture 39 (Fig. 8) fitting around a cylindrical portion 40 of the pin, and the pin has a flat circular head 41 bearing against the 45 register plate and holding it yieldingly against the head of screw 36. A spring 42 is housed in an enlarged portion of the bore of screw 36 and bears at its outer end against a washer 43 abutting a small head 44 formed 50 on the outer end of the pin, this spring tending to hold the head 41 of the pin against register plate 37. The screw 36 can be turned in either direction to adjust the position of the register plate, and to prevent the latter 55 from turning with the screw and for holding it at all times properly centered, there is provided a pin 45 fixed in bracket 30 vertically below screw 36 and having a reduced portion engaging the sides of a slot 46 cut in the 60 register plate from the circular aperture 39

to and through the lower edge of the plate. A set screw 47 is adapted to clamp screw 36 in adjusted positions.

Pivoted supported on a horizontal pin 48 projecting from the front and rear sides of the upstanding portion of bracket 30 adjacent the top thereof is a yoke shaped member 49, the connecting piece of the yoke extending along the outer side of the bracket and the sides of the yoke embracing the front and rear sides of the bracket. Integrally formed with each side of this yoke is a depending cam 50, 50', (Fig. 7) adapted to engage one of the shoulders 22, 22' of arm 17 and cause the latter to be moved about its pivot 19 when the pull guide is moved inwardly to engage a sheet.

It will be observed that there are two cams 50, 50', one on each side of bracket 30; and two shoulders 22, 22', one on each side of arm 17. Only one shoulder and its co-acting cam, however, is utilized after the mechanism has been positioned at one side or the other of the feed board, and the purpose of providing two pairs is to adapt the mechanism for location at either side of the feed board. As shown, the mechanism is located at the right hand side of the board, with reference to one facing the cylinder of the press, and in this position the cam 50 is adapted to co-act with the shoulder 22. Without alteration, the mechanism can be installed at the left hand side of the board, in which case the shoulder 22' would co-act with the cam 50'. To make this change, it would be necessary of course to reverse the position of the gauge plate 37. This can easily be done merely by pressing against the small head 44 of pin 38, to bring the reduced portion 51 of the pin in register with the slot 46 in the plate, whereupon the plate can be withdrawn upwardly, reversed by turning it through an angle of 180° about a vertical axis lying in its own plane, and then replaced. It is necessary to thus reverse the plate in order that it may extend across the path of the pull fingers, the plate being slotted, as shown, to provide a passage for said fingers.

Briefly, the operation of the mechanism is as follows: Bar 11, on which the pull guide is mounted, reciprocates in timed relation to the operations of the feeder and press to move the pull guide inwardly into engagement with each sheet when the sheet reaches a predetermined position on the board. During the inward movement of the pull guide the upper surface of shoulder 22, which is inclined to the plane of movement, comes into engagement with the relatively stationary cam 50, and the arm 17 is thereby caused to rotate about pin 19 against the pressure of spring 24, raising the pull fingers 16 to permit the margin of the sheet to enter the throat formed by these fingers with plate 15. When the sheet has fully entered this throat, the

shoulder 22 passes from under the cam 50 and the spring 24 causes fingers 16 to snap down on the sheet. The movement of bar 11 is now reversed to shift the sheet into registry 5 with plate 37, and during this outward movement of the pull guide the fingers are not opened, since the cam 50 when engaged by shoulder 22 turns idly about the pivot 48 and rides over the surface of the shoulder without exerting any pressure thereon, the cam finally leaving the shoulder when the pull guide has been retracted to its outer position, the position shown in Figs. 1 and 4. The engagement of the edge of the sheet with gauge 15 plate 37 stops the sheet and consequently in the continued outward movement of the pull guide fingers the sheet is disengaged therefrom, the pressure between the fingers and sheet being sufficiently light to permit disengagement 20 of the sheet without crumpling or otherwise injuring it, while being sufficiently positive to shift the sheets into registry.

Although one embodiment of the invention has been described in detail, the invention is 25 not limited to this one form but includes modifications and changes coming within the scope of the appended claims.

Having thus described the invention, what is claimed as new and desired to be secured 30 by Letters Patent is:

1. Sheet registering mechanism comprising, in combination, a bracket mounted to reciprocate in a path transverse to the direction of travel of the sheets, an arm pivoted to the 35 bracket on an axis transverse to said path and having means to press the margins of the sheets against a surface on said bracket, said arm extending from the opposite side of its pivot from said means and having formed therewith an upwardly projecting barrel, a pin screwed in said barrel and projecting from the top thereof, a coiled compression spring acting upwardly against said pin, an adjusting collar on the projecting end of said 40 pin slidable but non-rotatable with respect thereto, and a compression spring between the head of said pin and said collar.

2. In side gauge mechanism for sheet handling machines, an adjustable pull finger 45 comprising a pivoted arm having means at one side of the pivot to engage a sheet and formed at the other side of the pivot with an upwardly extending bore, a pin screwed in said bore, a spring acting upwardly against the lower end of said pin, and means to adjust the tension of said spring comprising a collar on said pin slidable but non-rotatable with respect thereto.

3. In side gauge mechanism for sheet handling machines, an adjustable pull finger 50 comprising a pivoted arm having means at one side of the pivot to engage a sheet and formed at the other side of the pivot with an upwardly extending barrel, a pin screwed in said barrel and projecting from the top there-

of, a spring acting upwardly against the lower end of said pin, a collar on the projecting portion of said pin slidable but non-rotatable with respect thereto having interlocking engagement with said barrel, and a compression spring between said collar and the head of said pin.

4. Sheet registering mechanism comprising, in combination, a bracket mounted to reciprocate in a path transverse to the travel of the sheets, a pivoted arm having means at one side of the pivot for engaging a sheet and formed with opposite laterally projecting shoulders at the other side of the pivot, a spring yieldingly holding the arm in sheet 75 engaging position, a stationary bracket at one side of the reciprocating bracket, a reversible sheet gauge mounted thereon, and two cams mounted at opposite sides of said stationary bracket for engagement with said shoulders, whereby the mechanism is adapted to be mounted at either side of a feed board.

5. Sheet registering mechanism comprising, in combination with a pull finger reciprocable in a path transverse to the travel of the sheets, a stationary bracket at one side of said reciprocating finger, a gauge plate extending transverse to the path of said finger, a screw threaded in said bracket, means for supporting said plate on said screw so that 90 the screw may be turned relatively to the plate to adjust the position of the latter, and means for holding the plate against rotary movement.

6. In side register mechanism for sheet 100 handling machines, a bracket mounted at one side of the feed board, a screw threaded in said bracket formed with an axial bore, a pin slidably mounted in said bore, a gauge plate on said pin adapted to be clamped between the head of the pin and the head of the screw, a compression spring in said bore acting 105 against the opposite end of said pin, and means to hold the plate against rotary movement.

7. The combination set forth in claim 6 in which said means comprises a pin projecting from said bracket and engaging a slot in said plate.

8. In side register mechanism for sheet 115 handling machines, a bracket mounted at one side of the feed board, a screw threaded in said bracket formed with an axial bore, a pin slidably mounted in said bore, a gauge plate having an aperture engaged with said pin 120 between the head of the pin and the end of the screw and having a slot extending from said aperture to and through the edge of the plate, said pin having a reduced portion whereby the plate can be removed and reversed by sliding the reduced portion into registry with the slot, and means for yieldingly holding the head of said pin against said plate.

9. In side register mechanism for sheet 130

handling machines, a bracket adapted to be mounted at one side of the feed board, a screw threaded in said bracket formed with an axial bore, a pin slidably mounted in said bore, a gauge plate having an aperture engaged with said pin between the head of the pin and the end of the screw and having a slot extending from said aperture to and through the edge of the plate, said pin having a reduced portion, whereby the plate can be removed and reversed by sliding the reduced portion into registry with the slot, a pin projecting from the bracket and engaging the slot in said plate, and means for yieldingly holding the head of the pin against said plate.

10. Sheet registering mechanism comprising, in combination, a bracket reciprocable in a path transverse to the direction of travel 20 of the sheets, an arm pivoted to said bracket on an axis substantially parallel to said direction, a finger carried by the free end of said arm and adapted to co-act with a surface on said bracket, said arm being provided with an extension on the other side of its pivot, an adjustable compression spring disposed between said extension and a portion of said bracket and tending to cause said arm to hold said finger engaged with said surface, spring retaining means formed in said arm extension and in said bracket, and means for operating said arm in the inward movement of the bracket toward the sheets.

30 11. Sheet registering mechanism comprising, in combination, a bracket mounted to reciprocate in a path transverse to the travel of the sheets, a pivoted arm having means at one side of the pivot for engaging a sheet 40 and a portion formed with an inclined surface at the other side of the pivot, a spring adapted to yieldingly hold said arm in sheet engaging position, a stationary bracket adjacent the path of the reciprocating bracket, 45 a cam lever pivoted to said stationary bracket and adapted to be swung idly by said portion of said pivoted arm during outward movement of said reciprocating bracket, and an angular arm projecting rearwardly and laterally from said cam lever and adapted to abut the rear surface of said stationary bracket during inward movement of said reciprocating bracket toward the sheets, whereby the inward movement of said cam lever 55 is limited and said cam lever is adapted to cooperate with said inclined surface to actuate the pivoted arm to engage a sheet.

12. Sheet registering mechanism comprising, in combination, a bracket mounted to reciprocate in a path transverse to the travel 60 of the sheets, a pivoted arm having means at one side of the pivot for engaging a sheet and portions formed with inclined surfaces on either side of the opposite end of said arm, a spring adapted to yieldingly hold said

arm in sheet engaging position, a stationary bracket adjacent the path of the reciprocating bracket, a cam lever pivoted to each side of said stationary bracket and adapted to be swung idly by one of said portions of said pivoted arm during outward movement of said reciprocating bracket, and a member rigidly connecting said cam levers and adapted to abut the rear surface of said stationary bracket during inward movement of said reciprocating bracket toward the sheets, whereby the inward movement of said cam levers is limited and one of said cam levers is adapted to cooperate with one of said inclined surfaces to actuate the pivoted arm to engage a sheet, said arrangement being such that the mechanism is adapted to be mounted at either side of a feed board.

13. Sheet registering mechanism comprising, in combination with a pull finger reciprocable in a path transverse to the travel of the sheets, a stationary bracket adjacent said reciprocating finger, a gauge plate extending transversely to the path of said finger, and a resilient, quick-detachable means for securing said gauge plate to said stationary bracket.

14. Sheet registering mechanism comprising, in combination with a pull finger reciprocable in a path transverse to the travel of the sheets, a stationary bracket adjacent said reciprocating finger, a gauge plate extending transversely to the path of said finger, a spring pressed locking means for detachably securing said gauge plate to said stationary bracket, and means for adjusting the position of said gauge plate relative to the stationary bracket.

In testimony whereof I hereunto affix my signature.

WILLIAM M. KELLY.
